DESIGN FOR A FENDER SPLASH GUARD

Bert G. Cochrane, Chicago, Ill., assignor to Casco Products Corporation, Bridgeport, Conn., a corporation of Connecticut

Application December 9, 1936, Serial No. 66,399

Term of patent 7 years

To all whom it may concern:

Be it known that I, Bert G. Cochrane, a citizen of the United States, residing at Chicago, in the county of Cook and State of Illinois, have invented a new, original, and ornamental Design for a Fender Splash Guard, of which the following is a specification, reference being had to the accompanying drawing, forming part thereof.

Fig. 2 is a top edge view of the ornament and fender splash guard.

The reverse side of the fender splash guard is substantially plain and unornamented.

I claim:

The ornamental design for a fender splash guard, as shown and described.

BERT G. COCHRANE.
